UNITED STATES PATENT OFFICE.

WILHELM RUDOLPH AND GUSTAV WOLFF, OF KIEL, GERMANY, ASSIGNORS TO SIGNAL GESELLSCHAFT MIT BESCHRÄNKTER HAFTUNG, OF KIEL, GERMANY, A FIRM.

SUBMARINE DIRECTION FINDER.

Application filed October 24, 1922, Serial No. 596,690, and in Germany October 9, 1922.

The invention relates to sound receiving plants in connection with ships, adapted to ascertain the direction of arriving sound waves. It has been found that disturbances of different kinds arise if the receivers of such plants are arranged within the ship or directly in the wall of the ship or in the near vicinity to it. These disturbances are caused by the proximity of the air filled volume of the body of the ship itself, the sound waves being lessened by this volume; besides this interference occurs due to sound waves arriving directly through the water to the receivers coacting with sound waves transmitted through the iron walls of the ship; another disadvantage arises from deflection and reflection of sound waves by the body of the ship.

According to the invention the receivers of a sound direction ascertaining plant are arranged outside the horizontal sound shadow of the body of the ship and practically open to the arriving sound from all directions, and rigidly connected to the ship.

On normal ships the receivers may be arranged below the bottom of the ship, on submarines it is to be preferred to mount them above the upper deck. Preferably they are connected to rigid brackets and enveloped by a rigid hollow casing filled with water and rigidly connected with the ship. Openings in the wall of this casing may allow the water of the sea to enter, and the casing itself preferably may be of stream line shape.

Figure 1 shows a sound direction ascertaining plant upon a submarine boat with two receivers above the upper deck and one receiver upon the tower.

Figure 2 shows a plan view of the boat shown in Fig. 1.

In Figure 1 the watertight body of the submarine is represented by 3. The outer shell 1 of the boat carries the hollow casing 9 the inner space of which communicates through openings 4, 4 with the outside water. Within this casing two receivers 6, 6 are mounted upon the upper ends of brackets which are rigidly connected to the outer shell 1 of the main body 3.

The pair of receivers 6, 6 permits the operator to ascertain the direction of the arriving sound by any of the well known "base-methods;" i. e., by measuring the time interval between the arriving of one and the same sound at the two receivers, or by observing maxima

or minima of sound caused by interference of sound waves, or by sensing the direction.

Another receiver 7 adapted to be used alone for ascertaining the direction of sound (that is, a directionally responsive receiver) is arranged above the top of the tower 8 of the submarine within a similar casing as described before. Such a receiver is shown, for example, in Patent No. 1,636,576, issued July 19, 1927.

Figure 2 shows the same apparatus as Figure 1 but in plan view. From this figure it can be seen that the tower 8 would not exercise any appreciable screening effect upon the receivers 6 since the latter are placed in the bow of the vessel whereas the tower is amidships. The sound shadow effect of the conning tower upon the receiver 6 could at most be the small angle included between the lines AA in Figure 2 but practically due to diffraction at the edges of the tower and other causes would be entirely negligible. The receivers therefore are each and all substantially freely accessible to sound waves coming from all horizontal directions. Receivers so mounted may be said to be substantially outside the horizontal sound shadow of the ship.

The different methods of ascertaining the direction of sound are not the object of the invention; instead, the most important feature of the invention is the fact, that the receivers themselves are free of disturbances caused by the vicinity of the body of the ship, and are freely accessible to sound waves coming through the water.

What we claim is:

1. In combination with a ship, a sound receiver adapted to receive sounds from substantially all directions, means for mounting said receiver at a fixed distance from the ship and for firmly fixing it thereto, said receiver being positioned so as to be freely accessible to sound waves from all horizontal directions.

2. In a submarine sound receiving plant associated with a ship and adapted to ascertain the direction of sound waves, a plurality of sound receivers, means for mounting said receivers at a fixed distance from the ship's body and rigidly connecting them thereto, a water-filled casing surrounding said receivers, said receivers being positioned so as to be freely accessible to the arriving sound waves from all directions.

3. Submarine sound receiving equipment for ships, comprising a plurality of sound re-

ceivers, means for mounting said receivers at a fixed distance from the body of the ship and rigidly connecting them thereto, a water-filled casing surrounding the receivers, said receivers being positioned substantially outside of the horizontal sound shadow of the ship, whereby the receivers will be freely accessible to the arriving sound waves from all direc-

tions and substantially free of disturbances arising from the proximity of the ship and its motion through the water. 10

In testimony whereof we affix our signatures.

WILHELM RUDOLPH.
GUSTAV WOLFF.
